US0D1012615S

(12) **United States Design Patent** (10) **Patent No.:** **US D1,012,615 S**
Yang (45) **Date of Patent:** **** Jan. 30, 2024**

(54) **ALL IN ONE TODDLER CUP WITH SNACK CONTAINER, STRAW AND HANDLE**

(71) Applicant: **Li Yang**, Jinhua (CN)

(72) Inventor: **Li Yang**, Jinhua (CN)

(**) Term: **15 Years**

(21) Appl. No.: **29/822,254**

(22) Filed: **Jan. 7, 2022**

(51) LOC (14) Cl. **07-01**

(52) U.S. Cl.

USPC **D7/507; D7/510; D7/532**

(58) **Field of Classification Search**

USPC D3/202; D7/300, 300.1, 392, 392.1, 393, D7/394, 396.1, 396.2, 507, 509, 510, 511, D7/513, 523, 529, 532, 533, 534, 591, D7/608, 900, 300.2, 202, 392.2; D8/394; D9/415, 438, 440, 442, 443, 447, 449, D9/516, 517, 525, 545, 546, 550, 554, D9/556, 563, 445, 434-436, 500-504, D9/538, 435; D19/20; D20/18, 19, 22; D24/197; 40/310, 324; 220/200, 210, 220/212.5, 288, 523, 709, 711, 717, 703, 220/710.5; 222/11.1, 11.4, 11.5, 480, 222/507, 546, 548, 553; D40/310, 324; 215/11.1, 11.4, 11.5, 12.1

(57) **CLAIM**

The ornamental design for an all in one toddler cup with snack container, straw and handle, substantially as shown and described.

DESCRIPTION

FIG. 1 is a front perspective view of an all in one toddler cup with snack container, straw and handle, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 7 Drawing Sheets
